UNITED STATES PATENT OFFICE.

JOHN C. ZELLER, OF WATFORD CITY, NORTH DAKOTA.

DISPLAY RACK.

Application filed July 27, 1928. Serial No. 295,803.

This invention relates to new and useful improvements in display racks, and particularly display racks for supporting and displaying large rolls of material, such as carpet or linoleum rugs, and the like.

Smaller dealers have no facilities, and no space for displaying such rugs, therefore such dealers do not care to carry any amount of stock, in such an article. If any stock is carried, the rolls are placed in a corner, or must be stored in another room. In either case, the rugs cannot be readily seen by the customers. Furthermore, when the rugs are thus disposed, great danger of the rugs falling is experienced, and considerable labor is required to take them down and replace them.

The principal object of the present invention is to provide a rack in which a number of rugs of this character may be displayed to the view of the customers.

Another object is to provide a rack wherein the rugs will be held against falling.

A further object is to provide a display rack, of this character, which renders the removal and replacing of the rugs easy.

Other objects and advantages will be apparent from the following description when taken in connection with the accompanying drawing.

In the drawing:

Figure 1 is a front elevation of a display rack made in accordance with the present invention, and showing several rugs therein, while one of the retaining latches is shown open, to permit removal of the rug.

Figure 2 is a vertical detail sectional view on the line 2—2 of Figure 1.

Figure 3 is a horizontal sectional view on the line 3—3 of Figure 1.

Referring particularly to the accompanying drawing, the rack includes the bottom member 10, to the ends of which are secured the vertical parallel side members 11, such side and bottom members being connected by the vertical back member 12. Extending across the forward edge of the bottom member, and being secured thereto, and to the forward edges of the side members, is a strip 13, such strip projecting above the bottom member to a slight degree, whereby to prevent the lower ends of the rugs from slipping outwardly from the rack. Secured to the upper portion of the forward face of the back member are the forwardly extending parallel division members 14, which maintain the rugs

out of contact with each other. Secured to the upper face of the bottom member, and extending forwardly and rearwardly thereof, are the strips or battens 15, for separating the lower ends of the rugs, which rest on said bottom member. It will be noted that the forward ends of the division members 14 are disposed in the plane of the forward edge faces of the side members 11. Mounted on the forward edge face of one of the side members 11, by means of a headed pivot 16, is a latch bar 17, the free end of which is formed with a notch 18, in the lower edge thereof, for engagement on a similar headed pivot 19 carried by the forward face of the adjacent division member 14. Also carried by this headed member 19, is a second latch bar 20, which has its free end formed with the notch 21 for engagement with another headed member 22, carried by the next division member. It will be noted that the heads of the members 19 and 22 are spaced from the division members sufficiently to accommodate the pivotal end of one latch bar, and the free end of the next one which engages therewith.

The latch bars, when properly engaged with their headed members serve to brace the division members 14, so that lateral movement thereof, by contact of a rug therewith, is prevented.

In the illustration there are shown three compartments for rugs, but this number may be increased as the conditions warrant. The rack is adapted to be placed at some conspicuous point in a store, so that the rugs contained therein may be readily inspected by the customers, and permit the storekeeper to quickly and easily swing any one of the rugs down to the floor, for the inspection of a customer, and as easily resorted to its place in the rack.

The free end of each of the latch members is turned outwardly, as shown at 23, to form a grip, whereby the latch may be raised or lowered.

It will be observed that when any one of the latch members is disengaged, for the purpose of removing a rug, the remaining engaged latch members properly brace the division members 14, so that should the remaining rugs fall against said division members, such members will be firmly held against movement.

What is claimed is:

1. A display rack including a box having an open front and top, vertical division mem-

bers in the box for separating the articles to be held by the box, and latch members pivotally mounted on the outer ends of the division members for retaining the articles in position between said division members, the pivot of each latch member serving as a keeper for the next adjacent latch member.

2. A display rack including a vertical box having its front and top walls removed, outwardly extending division members for separating the articles to be displayed, headed members carried by the front ends of the division members, and transverse latch bars pivotally supported on the headed members and each having a notch for the reception of the headed member of the next adjacent divi-

sion member whereby to retain the articles in position and to brace the division members against lateral movement.

3. A display rack comprising a vertical box including side, rear and bottom walls, division members carried by and extending forwardly from the rear wall in parallel relation with the side walls, division battens on the bottom wall for separating the articles, and combined latch and brace members pivotally carried by the said side wall and said division, each being in releasable latching engagement with the pivot of an adjacent latch.

In testimony whereof, I affix my signature.

JOHN C. ZELLER.
